UNITED STATES PATENT OFFICE.

WILLIAM B. ELTONHEAD, OF PHILADELPHIA, PENNSYLVANIA, ASSIGNOR
TO ED. Y. ELTONHEAD, OF SAME PLACE.

CONDUIT FOR ELECTRICAL CONDUCTORS.

SPECIFICATION forming part of Letters Patent No. 269,568, dated December 26, 1882.

Application filed August 17, 1881. (No model.)

To all whom it may concern:

Be it known that I, WILLIAM B. ELTONHEAD, of the city and county of Philadelphia, and State of Pennsylvania, have invented certain new and useful Improvements in Conduits for Electrical Conductors, applicable to purposes of telegraphy, electric lighting, and the distribution of power; and I do hereby declare the following to be a sufficiently full, clear, and exact description thereof to enable others skilled in the art to make and use the said invention.

The nature of my invention may be briefly stated to consist of a tube or trough formed of interlocking segments of non-conducting material united by clamps and bell-joints or screw-joints, so as to be susceptible of being opened and closed at any point in its length; also, in a series of hangers combined with such segmental pipes, whereby the pipes may be readily erected and supported safely in tunnels, sewers, and upon buildings.

I will now proceed to particularly describe the mode of making and using the said invention, referring in so doing to the drawings annexed, and to letters of reference marked thereon.

Figure 1 shows an elevation of the apparatus; Fig. 1^A shows an enlarged sectional view in vertical transverse section; Fig. 2, a vertical transverse section with the hanger or clamp, hereinafter described, applied; Fig. 3, a longitudinal section of segments forming the outer shell or casing; Fig. 4, a vertical transverse section of two internal segments; Fig. 5, a longitudinal section of parts of segments of the conduit as assembled; Fig. 6, an elevation of the bell-joint uniting the external shell and the internal form thereof, indicated by dotted lines; and Figs. 7 and 8 show in end and side elevation one of the clamping-hangers drawn on an enlarged scale.

The same letters of reference apply to the same parts in the several figures.

A represents a tube formed of two or more concentric series of parallel staves or segments, B, having rabbets C formed in the ends, fitting with corresponding rabbets, E, upon the next segment, G, in length of that series, and when assembled this series of segments form an external shell or tube, marked

J. (See Figs. 2, 4, and 5.) The several series of segments B and G are so assembled that the longitudinal seam of the inner segment, B, is covered by the central portion of the segment G, as shown in Figs. 1, 1^A, 2, and 4. 55 The transverse seams or joints of the segments G are so located in relation to the transverse seams of the inner segments, B, that seams of the latter are covered by the outer segments, as indicated in Fig. 5. The segments G of 60 the outer series are provided at one end of each with a bell-shaped expansion having annular grooves I therein, and the other end has corresponding rings or ridges, K, adapted to fit therein, so that when assembled the ridges 65 K fit in the grooves I, as shown in Fig. 6. Hangers or divided clamping-rings L, having a projecting tang or spur adapted to be inserted into the wall or arch of a culvert, as shown in Figs. 1 and 2, and which are made of enameled 70 metal of such form as to be susceptible of opening and closing, as shown in Figs. 7 and 8, serve to support the casing G, and embrace the several segments forming the outer casing or shell, G, at the part where the bell of one 75 section contains the smaller end of the next section, clamps the internally-grooved segments of the bell end upon the threads or convex annular ridges of the next section inclosed therein and holds them securely together, and 80 thus simultaneously secures the closure of both the longitudinal and transverse joints of the sections embraced, and the hangers or clamps L, by reason of being divided and bolted together, so as to open and close, enable them 85 to be readily applied and removed, and permit of ready access to any part of the electrical conductor without disturbing any other considerable part of the casing.

The conductors may be insulated from each 90 other in any of the usual modes; but I prefer to separate them by continuous grooved blocks of vitreous material, (marked N,) and to fill the interstices with any fusible or plastic non-conductor, this mode permitting repairs of one 95 conductor without seriously interrupting the use of the adjacent conductors. The whole furnishes an efficient means of protecting conductors placed in underground passages, and at the same time secures the greatest facility 100

for inspection and repairs of one part without disturbing others.

The conduits and supports for the conductors are made of vitrified earthenware, furnace-slag, glass, enameled metal, or other suitable non-conducting surface.

Having described my invention and the mode of making and using the same, what I claim as new and useful therein as originally 10 of my invention is—

1. A conduit for insulating and protecting electrical conductors, consisting essentially of tubes formed in sections and segments of vitrified earthenware, enameled metal, or glass, 15 with transverse grooves or threads adapted to interlock, and combined with the detachable clamping-hangers L, substantially as set forth.

2. In a conduit for electrical conductors, the combination, with a tube made in segments,

of segments located within the tube and provided with grooved peripheries for holding the wires, the inner and outer segments being composed of non-conducting material or conducting material coated with a non-conducting substance, substantially as set forth.

3. The combination, in an insulating-conduit for electrical conductors, of tubular wire supports made in segmental sections of a non-conducting material, with a non-conducting inclosing tube, made also in segmental sections and united by clamping-hangers formed of metal and protected by enamel, substantially as and for the purpose set forth.

WM. B. ELTONHEAD.
